UNITED STATES PATENT OFFICE

172,992

WRIST WATCH CASE

Paul A. Schwankhaus, Dayton, Ky., assignor, by
mesne assignments, to Elgin National Watch
Company, Elgin, Ill., a corporation of Illinois

Application February 14, 1952, Serial No. 18,516

Term of patent 14 years

(Cl. D42—8)

To all whom it may concern:

Be it known that I, Paul A. Schwankhaus, a citizen of the United States of America, residing at Dayton, in the county of Campbell and Commonwealth of Kentucky, have invented a new, original, and ornamental Design for a Wrist Watch Case, of which the following is a specification, reference being had to the accompanying drawing, forming a part hereof.

Fig. 1 is a face view of a wrist watch case, showing my new design, with the dominant features thereof shown in full lines.

Fig. 2 is a side view thereof.

I claim:

The ornamental design for a wrist watch case, as shown.
